US0D1045913S

(12) **United States Design Patent** (10) **Patent No.:** **US D1,045,913 S**
Gangishetty et al. (45) **Date of Patent:** **** Oct. 8, 2024**

(54) **DISPLAY SCREEN OR PORTION THEREOF WITH GRAPHICAL USER INTERFACE**

(71) Applicant: **Caterpillar Inc.**, Peoria, IL (US)

(72) Inventors: **Ramya Gangishetty**, Dunlap, IL (US); **Keith R. Folken**, West Peoria, IL (US); **Russell Loring Stott**, Chapin, SC (US); **Patrick Cozad**, Canton, IL (US); **Varun K. Yellichetty**, Houston, TX (US); **Rajendra Behara**, Bangalore (IN); **Jennifer Heine**, Mannheim (DE); **Venu Sri Sabbavarapu**, Peoria, IL (US)

(73) Assignee: **Caterpillar Inc.**, Peoria, IL (US)

(**) Term: **15 Years**

(21) Appl. No.: **29/888,489**

(22) Filed: **Mar. 31, 2023**

(51) LOC (14) Cl. **14-04**

(52) U.S. Cl.

USPC **D14/485**

(57) **CLAIM**

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

The sole FIGURE is a front view of a display screen or portion thereof with graphical user interface showing our new design.

The peripheral dashed broken lines depict a display screen or portion thereof, and form no part of the claimed design. The interior broken lines depict portions of the graphical user interface which form no part of the claimed design.
